10 Claims. (Cl. 263—47)

ABSTRACT OF THE DISCLOSURE

A separator for use between stacked coils of steel strip within an annealing cover, the separator permitting circulation of atmosphere gas. The separator is fabricated from a plurality of identical flanged steel segments in a manner to provide strength, adequate coil supporting area and direct gas to strip contact.

This invention relates to a gas circulating separator and more particularly to separators which are provided between stacked coils of steel within the inner cover of a box annealing furnace. In these furnaces, atmosphere gas is circulated throughout the stacked coils within the inner cover. It is desired to have as much gas in direct contact with the steel as possible in order to obtain maximum heat transfer. On the other hand, it is desirable to provide maximum supporting area for the coils on the separator to prevent damage to the edges of the steel being annealed.

Menough Patent Nos. 2,981,529 and 2,981,530, both dated Apr. 25, 1961, disclose separators for this purpose. However, the separators disclosed in these patents do not have the most desirable combination of area of gas contact and area of coil support. Manufacturing costs of these separators are relatively high and maximum strength is not obtained from the material used in the construction of the separators.

It is, therefore, an object of our invention to provide a coil separator which provides the most desirable combination of area of gas contact and area of coil support.

Another object is to provide such a separator having maximum strength for the weight of material used therein.

Still another object is to provide such a separator which is relatively inexpensive to manufacture.

These and other objects will be more apparent after referring to the following specification and attached drawing, in which:

FIGURE 1 is a top plan view of our separator with parts broken away;

FIGURE 2 is a view, on an enlarged scale, taken on the line II—II of FIGURE 1, but showing only the outer periphery of the separator;

FIGURE 3 is a plan view of one segment of the separator; and

FIGURE 4 is an end view of the segment of FIGURE 3.

Referring more particularly to the drawing, reference numeral 2 indicates the top surface of the separator and numeral 4 the bottom surface thereof. The separator is provided with the usual central opening 6 through which the atmospheric gas passes. The separator has a plurality of spaced apart closed passages 8 extending radially from the opening 6 to the outer periphery of the separator, a plurality of downwardly extending open radial channels 10, and a plurality of upwardly extending open radial channels 12, the channels 10 and 12 being alternately arranged at the sides of passages 8. Channels 10 and 12 and passages 8 increase in cross sectional area from the inner to the outer end thereof.

The separator is fabricated from a plurality of chan-

2

nel-like steel segments 14 which are all of the same size and shape. Each segment 14 includes a flat web 16 and a longitudinal flange 18 along each edge thereof. A radial slot 20 is provided in the inner end of web 16 and a similar slot 22 at the outer end thereof. The outer end of web 16 is shown as having a straight portion 24 and tapered side portions 26. However, this shape may be changed as desired. The steel segments 14 are cut from flat plates and the flanges 18 are then formed in a press, the slots 20 and 22 serving to center the plate in the press. In assembling the separator, a plurality of segments 14 are disposed in a horizontal plane with their flanges 18 extending upwardly and with a space equal to the width of the channel 10 therebetween as best shown in FIGURE 2. The same number of segments 14 are then disposed between the first segments with their webs in a horizontal plane and the flanges 18 extending downwardly, the second group of segments 14 being arranged with their webs 16 resting on top of the flanges 18 of the first group of segments 14 and their flanges 18 resting on top of the webs 16 of the first group. The slots 20 and 22 aid in centering the segments 14 when assembling the separator and also assist in preventing distortion of the separator due to expansion and contraction during the annealing cycle. With the segments 14 so assembled, it is a simple matter to connect the flanges of the top segments 14 to the webs of the bottom sections 12 by means of welds 28. The partly assembled unit is then turned upside down and the flanges of the then top sections are welded to the then bottom sections by means of welds 30. The separator is then ready for use.

It will be seen that this construction provides a box section forming each closed passage 8 which greatly increases the strength of the separator. It will also be seen that the assembly of the unit is simple and that there is no problem in making the welds 28 and 30 since they are provided at locations readily accessible to the welders.

Because of arcs 32 connecting the flanges 18 to the web 16 and the arrangement of the segments 14, there will be direct contact of atmosphere gas with the top and bottom surface of the coils of steel over approximately one-third of their contact area with additional heat being supplied to the coils from the atmosphere gas flowing through passages 8 and channels 10 for the top surface of the coil or channels 12 for the bottom surface of the coil. The separator supporting surface for the coil is approximately two thirds of the entire area, which is adequate to support the coil without damage, especially since no sharp corners are provided between the supporting surfaces.

While one embodiment of our invention has been shown and described, it will be apparent that other adaptations and modifications may be made without departing from the scope of the following claims.

We claim:

1. A gas circulating separator having a central vertical opening and adapted to be interposed between the individual coils of a vertical pile of coils being annealed, which comprises a top surface in one horizontal plane, a bottom surface in a second horizontal plane, said surfaces extending from said central opening to the outer periphery of said separator, spaced apart closed passageways between said surfaces extending radially from the central opening to the outer periphery of the separator, and an open channel on each side of each closed passageway, one facing upwardly and interrupting said top surface and the other facing downwardly and interrupting said bottom surface, said passageways and channels increasing in cross sectional area from the inner to outer ends thereof and being open at each end.

2. A gas circulating separator according to claim 1 including a first group of spaced apart channel like segments each having a flat web and a longitudinal flange at each edge thereof, a second group of spaced apart channel like segments each having a flat web and a longitudinal flange at each edge thereof, the flanges of each of the segments of one group extending toward the webs of the segments of the other group at positions intermediate the longitudinal sides thereof, said webs each having a wide and narrow end and being arranged radially about a central opening with their narrow ends adjacent thereto, and means connecting the flanges of the segments of each group to the webs of the segments of the other group, the webs of said first group of segments forming said top surface and the webs of said second group forming said bottom surface, said closed passageways being formed between the webs and flanges of adjacent segments.

3. A gas circulating separator according to claim 2 including radial slots in the outer and inner ends of each segment.

4. A gas circulating separator according to claim 2 in which said means connecting the flanges of the segments of each group to the webs of the segments of the other group are welds in said open channels extending between the free ends of the flanges of the segments of one group and the inner surface of the webs of the segments of the other group.

5. A gas circulating separator according to claim 3 in which said means connecting the flanges of the segments of each group to the webs of the segments of the other group are welds in said open channels extending between the free ends of the flanges of the segments of one group and the inner surface of the webs of the segments of the other group.

6. A gas circulating separator according to claim 2 including arcuate connections between the flanges and web of each segment.

7. A gas circulating separator according to claim 6 including radial slots in the outer and inner ends of each segment.

8. A gas circulating separator according to claim 6 in which said means connecting the flanges of the segments of each group to the webs of the segments of the other group are welds in said open channels extending between the free ends of the flanges of the segments of one group and the inner surface of the webs of the segments of the other group.

9. A gas circulating separator according to claim 8 including radial slots in the outer and inner ends of each segment.

10. A gas circulating separator according to claim 1 including a first group of spaced apart segments forming said top surface, a second group of spaced apart segments forming said bottom surface, said segments each having a wide and narrow end and being arranged radially about a central opening with their narrow ends adjacent thereto, a vertical member secured to and extending downwardly from each longitudinal side of each top segment and secured to a bottom segment intermediate the longitudinal sides thereof, each of said upwardly facing channels being formed by a bottom segment and the adjacent vertical members of adjacent top segments, and a vertical member secured to and extending upwardly from each longitudinal side of each bottom segment and secured to a top segment intermediate the longitudinal sides thereof, each of said downwardly facing channels being formed by a top segment and the adjacent vertical members of adjacent bottom segments, said closed passageways being formed between adjacent top and bottom segments and the vertical members secured thereto.
